TUBULAR HEAT EXCHANGE APPARATUS

William Henry Millener, Guildford, England, assignor to Woodall-Duckham (1920) Limited, Guildford, England, a British company

Application July 25, 1944, Serial No. 546,492
In Great Britain August 27, 1943

12 Claims. (Cl. 257—222)

1

This invention relates to improvements in tubular apparatus for effecting heat exchange between fluids, such as heat exchangers and condensers. It is applied to apparatus of the floating-head type; and in which each of the fluids makes at least two parallel passes through the apparatus, the paths of the fluids inside and outside the tubes being essentially parallel.

In heat exchange apparatus of the floating-head type, the tubes conveying one of the fluids are built up into an integral assembly with the supply and exit manifolds at one and the same end, and with a transfer header or headers connecting the various banks of tubes at the other end, so that the complete tube assembly can be inserted into an enclosing shell through which the second fluid flows. In systems in which the fluid flowing outside the tubes makes two or more passes over the tubes, pass plates are inserted between the banks of tubes to guide the fluid in the appropriate paths. In a two- or four-pass system, the inlet and exit ports for the fluid flowing over the tubes can both be situated at the same end of the enclosing shell as the connections to the tubes.

It is often desirable that the exterior of the tubes should be cleaned and in such cases a construction in which good access can be obtained to all parts of the tube assembly after withdrawal from the shell will have important advantages over any arrangement in which the pass plates or baffles and their supports make the complete cleaning of the tube surfaces difficult or impossible.

The closer the outer edges of the pass plates can be extended to the interior of the shell, the less will be the amount of short circuiting of the externally-flowing fluid between the various passes, with a consequent improvement in efficiency. In the known constructions, there has of necessity been a certain gap between the edges of the pass plates and the shell, to permit the tube assembly being inserted in and withdrawn from the shell. Any arrangement which brings the edges of the pass plates into direct contact with the interior of the shell is therefore much to be preferred.

The usual arrangement of the tube assembly in a floating-head heat exchanger or condenser also implies that a rather large gap is left between the outermost tubes and the interior surface of the shell, and the fluid passing through this gap is consequently not in contact with the tubes, leading to a reduction in the efficiency of heat transfer. Any arrangement which reduces sub-

2

stantially this by-passing of the tubes by the externally-flowing fluid will consequently be advantageous and lead to an improved efficiency.

The present invention has each of the desirable features referred to in the three immediately preceding paragraphs. Firstly, free access, unrestricted by the presence of pass plates or baffles, can be obtained to the outsides of the tubes for cleaning when withdrawn from the shell, since the pass plates and baffles can be completely dismantled from the tube assembly. Secondly, the outer edges of the pass plates can be extended into direct contact with the interior of the shell, which substantially prevents short-circuiting of the externally-flowing fluid between different passes. Thirdly, the space between the outermost tubes and the shell can be adequately baffled to reduce the bypassing of the tubes by the fluid flowing in this space.

20 Various forms of the invention will now be described by way of example with reference to the accompanying drawings, in which:

Figure 1 is a vertical section through a four-pass condenser;

25 Figure 2 is a cross-section on the line 2—2 of Figure 1;

Figure 3 is an enlarged view of a detail of the device of Figure 1;

30 Figure 4 is an enlarged sectional detail showing spring-loaded pass plates applied to a four-pass arrangement;

Figure 5 is a view perpendicular to that of Figure 4;

35 Figure 6 is a cross-sectional view of a modification disclosing a two-pass condenser having a single pass plate;

Figure 7 is an enlarged view of a detail of Figure 6;

40 Figure 8 is a cross-sectional view of a two-pass condenser embodying a spring-loaded pass plate; and

Figure 9 is an enlarged view of a detail of Figure 8.

Referring to Figures 1, 2 and 3, the condenser 45 comprises an outer enclosing shell 10 with an inlet 11 and an outlet 12 for the fluid which flows externally over the tubes through which the second fluid flows. The tube assembly comprises inlet and outlet manifolds 13 and 14 respectively, 50 transfer headers 15, and banks of tubes 16 connecting the manifolds and the headers. The manifolds, tubes and headers are arranged to provide the desired number of passes for the internally-flowing fluid. The manifolds, tubes 55 and headers form a unitary assembly which can

be inserted into and withdrawn from the shell 10, in which the tube assembly is mounted by the flanges 9.

In order to provide the requisite number of passes for the externally-flowing fluid through the shell between the inlet and outlet, pass plates are arranged between the banks of tubes. In the construction shown, the externally-flowing fluid makes four passes, and two pass plates are therefore provided, arranged perpendicularly to each other across the interior of the shell, thus dividing the space into four quadrant sections. Each pass plate comprises two parts 17 and 17a, and 18 and 18a respectively. The inner portions of the two parts of each pass plate overlap as shown in Figures 2 and 3, thus bearing on each other at right angles round the central longitudinal axis of the condenser. Holes 21 are provided in the pass plates as shown in Figure 1 to transfer the fluid to successive passes.

From Figure 2, it is seen that if the two inner portions of the plate 17 and 17a are moved towards each other, the effect will be to move the outer edges of the two plates 18 and 18a outwards towards the inner surface of the shell 10, and similarly movement of the inner portions of the plates 18 and 18a together moves the outer edges of the parts 17 and 17a into contact with the shell. By moving the edges of the pass plates into contact with the interior of the shell after the tube assembly and pass plates have been inserted into the shell, short-circuiting of the externally-flowing fluid between the various passes through the gap between the edges of the pass plates and the shell is substantially prevented, and the efficiency of heat exchange is improved.

The parts of the pass plates are held together and moved when required by means of two sets of bolts as shown in detail in Figure 3. The bolts 19 act on the plates 17 and the bolts 20 on the plates 18. Each bolt passes through an aperture in one of the parts of the pass plate, and screws into a nut portion 19a or 20a respectively welded to the other part of the pass plate.

The pass plates are placed in position between the tubes when the tube assembly is withdrawn from the shell and the bolts 19 and 20 are screwed in loosely, so that the parts of the plates may be moved inwards a sufficient distance to enable the whole assembly to be inserted in the shell. When in position in the shell, the bolts are then tightened by means of a long-handled box spanner 22 inserted through closable apertures 23 in the shell 10, as shown in Figure 1. The positions of the various apertures 23 are arranged to correspond to the positions of the bolts. The outer edges of the pass plates are thereby moved outwards into contact with the interior of the shell, forming an effective seal between the various passes, while short-circuiting of fluid through the region where the pass plates meet on the axis is substantially prevented by their contact here, as shown in Figure 3. Conversely, when it is desired to remove the tube assembly from the shell, the bolts 19 and 20 are first loosened with the spanner through the apertures 23, so that the pass plates are withdrawn from contact with the shell, whereupon the whole assembly can be directly extracted from the shell.

In order to minimize by-passing of the tubes by fluid flowing through the spaces between the banks of tubes and the surfaces of the pass plates, subsidiary baffles 24 are provided at intervals across the spaces. The baffles 24 are attached perpendicularly to the surfaces of the pass plates.

Further, in order to minimize by-passing of the tubes by fluid flowing through the space between the outermost tubes and the inner surface of the shell (which space is caused by the size of the rim of the tube plate and the transfer headers 15), baffle rings are provided at intervals across this space. These baffle rings are formed of quadrant sections 25 attached by pin and slot connections between the outer portion of each subsidiary baffle 24 and a suitable projection 26 on the back of the adjacent part of the pass plate, as shown in Figure 2. The pin and slot connections permit the baffle ring sections 25 to move out towards the inner surface of the shell when the pass plates are extended into position, and vice versa.

It is seen that by removing the bolts 19 and 20 and the quadrant baffle rings 25, the pass plates can be dismantled completely from the tube assembly when the latter is removed from the enclosing shell, leaving the entire tube surface freely accessible for cleaning.

Figures 4 and 5 show a modification of the apparatus of Figures 1, 2 and 3, in which the bolts 19 and 20 are dispensed with, and the pass plates are extended into contact with the shell by means of springs. The springs 27 are flat L-shaped members, having one arm attached to the subsidiary baffle 24 while the other arm bears freely on the inner portion of the adjacent part of a pass plate. As seen from Figure 5, the springs 27 tend to move the inner portions of each part of a pass plate together, and so the effect is the same as that of the bolts 19 and 20. The parts of the pass plates are placed in position in the tube assembly and the quadrant baffle rings 25 are attached before the assembly is inserted into the shell. The edges of the pass plates near the head are then pressed in towards the axis sufficiently far to enable the head to be inserted into the opening of the shell, and the remainder of the tube assembly can then be pushed into the shell, the compression of the springs 27 acting to keep the outer edges of the pass plates pressed into contact with the inside of the shell. In the same way as in Figures 1, 2 and 3, the pass plates and baffles can be dismantled completely from the tube assembly.

Figures 6, 7, 8 and 9 show the present invention applied to a condenser in which the externally-flowing fluid makes two passes over the tubes.

Figures 6 and 7 show an arrangement in which the two parts of the pass plate are connected together and moved relatively to each other by screwed bolts. The pass plate is formed of two parts, one of which 28 extends diametrically across nearly the whole of the internal width of the shell 10, while the remaining part 29 is much narrower and serves to close the remaining gap. The part 29 is of L-section as shown clearly in Figure 7, and the part 28 has its edge 28a turned up at right angles. Screwed studs 30 are mounted in the part 29 as shown, and pass freely through apertures in the edge 28a. Rotation of a nut on stud 30 causes the vertical portion of part 29 to move towards part 28a, and so presses the edge 29a into contact with the inner surface of shell 10, and the remote edge of the pass plate into contact with the opposite side of the shell.

Baffle rings 31 which baffle the space between the outermost tubes and the shell as in the preceding constructions are now practically semi-

circular. The ends of the lower sections of the baffles 31 are attached to flat longitudinal members 32 extending over the length of the tubes (see Figure 7). The ends of the upper sections remote from the part 29 of the pass plate are attached to a similar longitudinal member 32a, while the other ends are attached to the part 29. Bolts 33 pass freely through apertures in the member 32 adjacent to the part 29 and screw into a nut portion 33a welded to the part 29.

The assembly and operation are very similar to those of Figures 1, 2 and 3. The two parts of the pass plate together with the baffle rings 31 are first mounted on the tube assembly with the nut on stud 30 and the bolt 33 loose, and the assembly is inserted in the shell. Access to the nuts and bolts is then obtainable through the closable apertures 23 in the shell (Figure 6). Tightening the nut on stud 30 extends the two edges of the pass plate into contact with the interior surface of the shell, while tightening the bolt 33 brings the edge of the part 29 into contact with the part 28 and so prevents fluid short-circuiting between the passes at this point. The bolt 33 also holds the annular baffles 31 in position. Before withdrawal of the assembly from the shell, the nuts and bolts are slackened through the apertures 23 and the whole assembly can then be freely withdrawn. By removing the nuts and bolts, the pass plate and the baffle rings can be completely dismantled from the tube assembly, leaving the latter fully accessible for cleaning.

Figures 8 and 9 show an arrangement, comparable to that of Figures 6 and 7, in which the nuts and bolts are replaced by springs. The pass plate is again formed of two parts 34 and 35, of which the part 34 extends across nearly the whole diameter of the shell 10 while the part 35 closes the space between the part 34 and the shell. Part 35 is slidably mounted on the edge of part 34 by means of the bolts 36 which pass through slots in the part 35 as shown in Figure 9. Between parts 34 and 35 are springs 37 which bear against the up-turned edge 35a, and act to move the two sections of the pass plate apart, thus pressing the edge 35a into contact with the shell at one side, and the remote edge of part 34 into contact with the shell on the opposite side.

Semi-circular baffle rings 31 are provided as in the preceding case. The ends of the lower sections of the baffles are attached at one end to a longitudinal member 38 which itself is attached to the part 34 of the pass plate; the other ends of these baffles are attached to a longitudinal member 39 on which the part 35 slides freely. The ends of the upper sections of the baffles 31 are attached to a similar longitudinal member 40 resting freely on the part 34, while the ends adjacent the part 35 are attached thereto as shown in Figure 9.

Insertion of the tube assembly and baffles in the shell is effected in a manner similar to that used for the arrangement of Figures 4 and 5. The two parts of the pass plate near the head of the tube assembly are first compressed until the head can be inserted in the shell opening, and the assembly is then pushed into position, the springs 37 operating to hold the edges of the pass plate against the inner surface of the shell. When withdrawn from the shell, the baffle rings and pass plate can be dismantled completely from the tube assembly to render the tubes freely accessible for cleaning.

What I claim is:

1. Tubular apparatus of the floating-head type for effecting heat exchange between fluids wherein the fluid flowing outside the tubes makes four parallel passes through the apparatus, including in combination a cylindrical enclosing shell of uniform diameter permanently closed at one end, a tube assembly incorporating four tube banks between inlet and outlet manifolds and a floating head, which tube assembly is insertable in and removable from the enclosing shell through the end opposite to the closed end, two pass plates arranged perpendicularly to one another across the interior of the shell, each of said pass plates being formed of two relatively movable and separable parts inserted between the tube banks with their inner portions overlapping, the inner edges of the parts of one pass plate bearing perpendicularly on the inner portions of the parts of the other pass plate, whereby movement of the two parts of one pass plate towards each other presses the outer edges of the two parts of the other pass plate into contact with the interior of the enclosing shell, and means to press the inner portions of the pass plates towards each other and the outer edges into contact with the interior of the enclosing shell when the tube assembly and the pass plates are inserted in the shell.
2. Heat exchange apparatus as claimed in claim 1, in which the two parts of a pass plate are held together and moved relatively to each other by means of bolts accessible through closable apertures in the enclosing shell.
3. Heat exchange apparatus as claimed in claim 1, in which the two parts of each pass plate are held together and moved relatively to each other by means of bolts accessible through closable apertures in the enclosing shell.
4. Heat exchange apparatus as claimed in claim 1, in which the two parts of each pass plate are held together and are moved relatively to each other by means of bolts accessible through closable apertures in the enclosing shell, which bolts are operated by means of a long-handled spanner inserted through the said apertures.
5. Heat exchange apparatus as claimed in claim 12, including a spring operative to press the outer edge of each part of a pass plate into contact with the enclosing shell.
6. Heat exchange apparatus as claimed in claim 1, including springs carried by the two parts of one pass plate and operative to press the inner portions of the two parts of the other pass plate towards each other.
7. Heat exchange apparatus as claimed in claim 12, including a longitudinal member joining the ends of each arcuate baffle remote from the ends connected to a part of a pass plate, said longitudinal member bearing on the other part of the said pass plate.
8. Heat exchange apparatus as claimed in claim 1, including quadrantal baffles baffling the space between the outermost tubes of the tube assembly and the interior of the enclosing shell arranged at intervals along the length of the tubes, and a non-rigid connection between the end of each quadrantal baffle and the adjacent part of a pass plate.
9. Heat exchange apparatus as claimed in claim 12, including subsidiary baffles projecting from the parts of a pass plate arranged at intervals along the length of the tubes and baffling the space between the tube banks.
10. Heat exchange apparatus as claimed in claim 1, including subsidiary baffles projecting from the parts of the pass plates arranged at

intervals along the length of the tubes and baffling the space between the tube banks.

11. Heat exchange apparatus as claimed in claim 1, including subsidiary baffles projecting from the parts of the pass plates arranged at intervals along the length of the tubes and baffling the space between the tube banks, quadrantal baffles baffling the space between the outermost tubes of the tube assembly and the enclosing shell, a non-rigid attachment between the outer end of a subsidiary baffle and one end of each quadrantal baffle, and a non-rigid attachment between the other end of each quadrantal baffle and the adjacent part of a pass plate.

12. Tubular apparatus of the floating-head type for effecting heat exchange between fluids, wherein each of the fluids makes at least two parallel passes through the apparatus, including in combination a cylindrical enclosing shell of uniform diameter permanently closed at one end; a tube assembly incorporating at least two tube banks between inlet and outlet manifolds and a

floating head, which tube assembly is insertable in and removable from the enclosing shell through the end opposite to the closed end; a pass plate formed of two relatively movable and separable parts inserted between the tube banks, each of said pass plate parts being entirely unattached to the tube assembly; arcuate baffles baffling the space between the outermost tubes of the tube assembly and the interior of the enclosing shell, arranged at intervals along the length of the tubes; a connection between one end of each of said arcuate baffles and a part of a pass plate; means to support the other end of each arcuate baffle adjacent to the edge of a pass plate and to the interior of the enclosing shell; and means to effect the movement of the two parts of the pass plate into contact with the interior of the enclosing shell when the tube assembly, the pass plate parts, and the arcuate baffles are inserted into the shell, while maintaining a seal between the two parts of the pass plate.

WILLIAM HENRY MILLENER.
